UNITED STATES PATENT OFFICE.

CHARLES GRAFF, OF NEW YORK, N. Y., ASSIGNOR TO FERDINAND FUCHS & BROTHERS, OF SAME PLACE.

DESIGN FOR A HOLDER FOR MATCHES AND CIGARETTES.

SPECIFICATION forming part of Design No. 21,468, dated April 19, 1892.

Application filed January 18, 1892. Serial No. 418,504. Term of patent 3½ years.

To all whom it may concern:

Be it known that I, CHARLES GRAFF, a citizen of the United States, residing in the city of New York, county and State of New York, 5 have invented and produced a new and original Design for Metal Holders or Receptacles for Cigarettes and Matches, of which the following is a specification, reference being had to the accompanying drawings, forming part thereof.

Figure 1 is a plan view of my newly-designed holder; and Fig. 2 is a side elevation of the same, such views being deemed necessary to fully illustrate the design.

15 The leading feature of my design consists in a lower surface A, and about which is a

convex outwardly-rolling flange a, such flange being extended toward the rear and formed with an opening B, while the front end of the surface A is bent in an upward angle or curve. 20 About the edge or rim of the flange a extends the repoussé chasing shown in the drawings, holding to the same style of ornamentation about the opening B.

I claim—

The design for a cigarette and match holder, 25 as herein described and shown.

CHARLES GRAFF.
